(57) **CLAIM**

The ornamental design for a skiving punch, as shown and described.

DESCRIPTION

FIG. 1 is a top elevation view of a skiving punch showing my new design;

FIG. 2 is a perspective view thereof;

FIG. 3 is a front elevation view thereof; and,

FIG. 4 is a side elevation view thereof.

The broken lines in the figures are for the purpose of illustrating environmental structure only and form no part of the claimed design.
